YARN CARRYING DEVICE

Julius Hommer, Union, N. J., assignor to Lapin Products, Inc., New York, N. Y., a corporation of New York

Application February 11, 1941, Serial No. 378,338

6 Claims. (Cl. 242—146)

The present invention relates to a yarn carrying device, and particularly relates to a transparent molded device formed of a synthetic plastic for carrying balls of yarn to be used in knitting.

In hand knitting it is desirable to provide some means to hold the ball of yarn so that it will be readily available to the knitter and so that the continued removal of yarn from the ball, particularly from the outside of the ball with resulting rolling and rocking of the ball, will not result in the yarn falling and becoming unwound, knotted or tangled.

Where the yarn is carried in a box on an adjacent table or even in an enclosure upon the floor, there is always a long strand of the yarn extending from the ball to the knitting needles which is liable to become tangled, knotted or caught in various objects, and which limits the movement of the knitter from place to place.

Ordinarily, it has not been readily possible for a person when walking or in going from place to place, to be able to knit from a ball of yarn.

Where handbags or similar containers are utilized, either the ball of yarn is held so loosely that too great a length of it becomes unwound and may become tangled, or snagged, or, on the other hand, the ball is held so tightly within a container that the yarn cannot be readily removed therefrom and the ball would not be readily turned as the yarn is withdrawn.

It is, therefore, among the objects of the present invention to make an improved yarn carrier of the character described which may be readily carried by and about the person and which will hold the ball of yarn and permit it to be readily turned or rotated as the yarn is withdrawn therefrom and which at the same time will hold the yarn with sufficient friction to prevent too great a length being inadvertently unraveled or uncoiled from the ball of yarn.

Another object is to provide a simple, inexpensive, readily manipulated and carried yarn carrier, which may receive and carry a supply of yarn and supply said yarn as needed to a person knitting, whether said person is standing, sitting or moving from place to place by foot or other conveyance, with assurance that the yarn will not become readily unwound, unraveled, uncoiled or knotted and tangled during its process of being removed from the ball of yarn in which it has been wound.

Still further objects and advantages will appear from the more detailed description set forth below, it being understood, however, that this

more detailed description is given by way of illustration and explanation only, and not by way of limitation, since various changes therein may be made by those skilled in the art without departing from the scope and spirit of the present invention.

In accomplishing the above objects of the present invention, it has been found most satisfactory to form the container of a plastic material, such as for example cellulose acetate or some other transparent or translucent synthetic resinous or plastic material, which will be light in weight and yet sufficiently transparent to permit observation of the ball of yarn as it is being consumed, and which at the same time will be so formed that it may be readily manipulated to enclose the ball of yarn or opened to permit insertion of a new ball of yarn.

In the preferred construction, it has been found most desirous to form a cylindrical container having a relatively flat bottom and a relatively rounded top, which container is preferably formed in two sections which separate along the middle of the side wall thereof and which may be readily closed by a bayonet connection, with assurance that such closure will not be readily disengaged by carrying of the ball of yarn.

In the preferred construction it has been found most suitable to form a central opening in the bottom of the carrier which will tend to center the yarn directly below a much smaller opening at the top of the carrier through which the yarn is removed and positioned.

Around the top of the yarn carrier it has been found most suitable to form a series of openings which upon contacting with the yarn will frictionally engage the same and reduce its tendency to become too rapidly pulled out or unwound or unraveled from the ball. Positioned on either side of the central opening are two openings or other elements for receiving a carrier or loop member which will permit the yarn carrier to be readily placed upon the arm or over the wrist of the person who is doing the knitting.

Referring to the drawings, which illustrate one of the embodiments according to the present invention, to which the invention is by no means restricted, since the drawings are merely by way of illustration and not by limitation,

Fig. 1 is a top perspective view of the carrier.
Fig. 2 is a transverse vertical sectional view upon an enlarged scale as compared to Fig. 1, upon the line 2—2 of Fig. 1.

Fig. 3 is a transverse sectional view upon the line 3—3 of Fig. 2.

Fig. 4 is an enlarged inside elevational view upon the arcuate line 4—4 of Fig. 3, upon an enlarged scale as compared to Fig. 3.

Fig. 5 is a fragmentary transverse sectional view upon the line 5—5 of Fig. 3, and upon an enlarged scale as compared to Fig. 3.

Fig. 5a is a transverse fragmentary sectional view upon the line 5a—5a of Fig. 3, upon an enlarged scale as compared to Fig. 3.

Fig. 6 is an enlarged fragmentary perspective view illustrating one of the locking lugs of the lower portion of the container or holder of Figs. 1 to 3, and

Figs. 7 to 9 are directed to a different embodiment for holding several balls of yarn, Fig. 7 being a top perspective view similar to Fig. 1, Fig. 8 being a transverse sectional view upon an enlarged scale as compared to Fig. 7 upon the line 8—8 of Fig. 7 and being similar to Fig. 2, and Fig. 9 being a transverse sectional view upon the line 9—9 of Fig. 8, similar to Fig. 3.

Referring particularly to Figs. 1 and 2, the upper section A and the lower section B having the locking connection C, may be formed by molding transparent plastic material, such as cellulose acetate, a urea formaldehyde resin, a vinylite resin, an acrylic resin, etc.

The ball of yarn as illustrated at D in Fig. 2 may be placed within the enclosure formed of the upper shell A and the lower shell B, and the entire carrier may be carried by the suspension member E which is designed to be fitted over the wrist.

Both shell sections A and B are provided with the cylindrical side walls 10 and 11, with the upper wall 10 having the reinforcing ridge 12, while the lower wall 11 is provided with the reinforcing ridges 13, 14, 15 and 16. The wall 10 is provided with a shoulder 17 against which abuts the upper edge 18 of the side wall 11 of the lower shell B.

Below the shoulder 17, the upper wall 10 is provided with enlarged depending portion 19. This enlarged portion 19 is provided with a beveled lower portion 20.

At intervals, which in the embodiment shown are 90° apart, such portion 19 is bulged outwardly and recessed at such bulged portions, as best shown in Figs. 2 and 5a, at 21 and has a slightly bulged out thin wall 22, which enables insertion of the outwardly extending tapered lugs 23 on the top edge 18 of the lower wall 11 (see particularly Fig. 6).

These tapered lugs, as best shown in Fig. 6, are provided with a relatively wide rear end 24 and a relatively narrow forward end 25 and at their top face 26 they are flushed with the upper edge 18 of the lower wall 11, while at their lower edge 27 they incline forwardly and upwardly.

As best shown in Figs. 3 and 4, the recess 21 has the side edge 28 which extends the full depth thereof, the upper top edge 29 and the short forward edge 30 which is below the groove or oblique slot 31 which extends upwardly away from the corner 32 of said recess 21.

The bottom of the groove or ridge 31, as best shown in Fig. 3, is somewhat elevated above or positioned inside of the bottom of the recess 21 and adjacent its end portion it has a ridge 33 extending across the groove or slot 31 a distance from the end of the groove 34 approximately equal to the width of the lug 23 of Fig. 6.

The lower portions of the side walls 11 are curved at 35 into the relatively flat bottom 37, which is inclined somewhat upwardly toward its central portion 38.

The bottom 38 is provided with a central opening 39, tending to center the ball of yarn and cause it to fall back into axial position from the position shown in Fig. 2.

The upper portion of the upper shell A is also curved inwardly as indicated at 40, and forms a dome 41 which at the top thereof is provided with the eyelet 42 through which the yarn passes upon being removed from the ball D. The eyelet 42 has a rounded inner face 44 which is of somewhat greater depth than thickness of the dome 41 of the shell so as to offer substantial friction to the yarn as it is being unwound from the ball of yarn D.

Around the dome 41, extending from the curved portion 40 up to adjacent the central eyelet 42, are the openings 45 which are almost circular as indicated at 46 in Fig. 1 adjacent the eyelet 42, but which become narrower and tapered as indicated at 47 and terminate at 48 (see Fig. 1).

When the yarn is pulled upwardly suddenly and too great a force is expended upon it, tending to cause it to unravel, the top of the ball of yarn will contact these openings and tend to be retarded in its movement with the result that the feed of yarn will be slowed or substantially stopped.

On each side of the eyelet 42 and between two of the openings 45 are positioned the diametrically opposed eyelets 49, which receive the lower ends 50 of the suspension member E. The knots 51 at the lower ends of the suspension member 50 hold the suspension member E in position.

In forming the shells A and B, each of the shells is preferably molded in one piece, together with the lugs 23, the recesses 21 and the grooves 31 and together with the openings 39 and 45 which may be formed therein or cut in afterwards. The suspension member E is attached to the upper shell A as a final operation.

In operation, by grasping the assembled upper shell A and lower shell B of Fig. 2 with different hands, they may be turned in opposite directions to remove the lugs 23 from the grooves 31 and over the latching ridges 33. When the backs 24 of the lugs 23 strike the walls 28, the lugs 23 may be withdrawn from the recesses 21, permitting disengagement between the upper shell A and the lower shell B. Then a ball of yarn D may be placed in position, or the ball of yarn in position may be replaced and its loose end may be inserted through the eyelet 42.

When the upper shell is to be connected to the lower shell B, the lugs 23 are inserted into the recesses 21 and the forward ends 25 of the lugs 23 are caused to engage in the ridges 31 adjacent their entrance 32. Then the upper shell A may be turned in respect to the lower shell B, forcing the wedge shaped lugs 23 into the grooves 31 past the ridges 33.

The wedge shape of the lugs 23, together with the resiliency of the side walls 10 and 11, will form a tight connection which will not become accidentally displaced even though the container may be carried and jiggled or may be struck against many objects in the course of usage.

The entire shells A and B are preferably made so thin that they will have sufficient resiliency to cause a firm locking together of the lugs 23 in the grooves 31 in the positions indicated in Figs. 3 and 5.

In the alternative embodiment of Figs. 7 to 9, (similarly functioning parts being indicated by the same letters and numerals as in Figs. 1 to 6, however, primed) the base B' is provided with

three receptacles 100 to receive three balls of yarn D', which may be of different colors or different grades or character of yarns to enable the knitting of a multi-effect or multi-colored pattern.

The bottom 37' of the base B' is caused to have upwardly extending portions 101, which act to separate the various pockets receiving the different balls of yarn D'. Three eyelets 42' are provided and through each of these eyelets a separate strand 43' from a ball of yarn D' may pass upwardly.

It is thus apparent that the applicant has provided a simple, inexpensive, readily transportable yarn carrier device which is of relatively thin construction, yet reinforced by the locking arrangement at C so that it may withstand constant handling and swinging.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

What is claimed is:

1. A plastic molded yarn carrier comprising one piece upper and lower hollow molded thin flexible transparent shell plastic members having a locking connection, a suspension member and means to permit removal of an end of yarn through the upper portion of the container, said upper and lower shell members telescoping together at said locking connection and said locking connection including interiorly positioned slots on one shell and interfitting wedges on the other shell, said locking connection including a plurality of obliquely upwardly extending grooves upon the inside edge of one of the thin shell members having an enlarged wide inlet notch with a ridge crossing said groove and elongated wedge shaped engaging members to be forced into said grooves on the outside edge of the other shell member.

2. A plastic molded yarn carrier comprising one piece upper and lower hollow molded thin flexible transparent shell plastic members having a locking connection, a suspension member and means to permit removal of an end of yarn through the upper portion of the container, the lower portion of the container being provided with a central opening to center the ball of yarn, said upper and lower shell members telescoping together at said locking connection and said locking connection including interiorly positioned slots on one shell and interfitting wedges on the other shell, said locking connection including a plurality of obliquely upwardly extending grooves upon the inside edge of one of the thin shell members having an enlarged wide inlet notch with a ridge crossing said groove and elongated wedge shaped engaging members to be forced into said grooves on the outside edge of the other shell member.

3. A plastic molded yarn carrier comprising one piece upper and lower hollow molded thin flexible transparent shell plastic members having

a locking connection, a suspension member and means to permit removal of an end of yarn through the upper portion of the container, the upper portion of the container being provided with spaced openings to frictionally retard unwinding of the ball of yarn, said upper and lower shell members telescoping together at said locking connection and said locking connection including interiorly positioned slots on one shell and interfitting wedges on the other shell, said locking connection including a plurality of obliquely upwardly extending grooves upon the inside edge of one of the thin shell members having an enlarged wide inlet notch with a ridge crossing said groove and elongated wedge shaped engaging members to be forced into said grooves on the outside edge of the other shell member.

4. A plastic molded yarn carrier comprising one piece upper and lower hollow molded thin flexible transparent shell plastic members having a locking connection, a suspension member and means to permit removal of an end of yarn through the upper portion of the container, the top of the container being provided with spaced eyelets, a central eyelet being provided for the egress of the yarn and outside eyelets being provided for the attachment of the suspension member, said upper and lower shell members telescoping together at said locking connection and said locking connection including interiorly positioned slots on one shell and interfitting wedges on the other shell, said locking connection including a plurality of obliquely upwardly extending grooves upon the inside edge of one of the thin shell members having an enlarged wide inlet notch with a ridge crossing said groove and elongated wedge shaped engaging members to be forced into said grooves on the outside edge of the other shell member.

5. A plastic molded yarn carrier comprising one piece upper and lower hollow molded thin flexible transparent shell plastic members having a locking connection, a suspension member and means to permit removal of an end of yarn through the upper portion of the container, the connection of the shells being provided by a plurality of recesses and grooves extending obliquely upwardly from the recesses on one member and interlocking lugs on the other member, said shells having a plurality of reinforcing ridges adjacent said locking connection.

6. A plastic molded yarn carrier comprising one piece upper and lower hollow molded thin flexible transparent shell plastic members having a locking connection, a suspension member and means to permit removal of an end of yarn through the upper portion of the container, the bottom of said carrier having a plurality of cup members to receive a plurality of balls of yarn and to keep them separated from one another, said locking connection including a plurality of obliquely upwardly extending grooves upon the inside edge of one of the thin shell members having an enlarged wide inlet notch with a ridge crossing said groove and elongated wedge shaped engaging members to be forced into said grooves on the outside edge of the other shell member.

JULIUS HOMMER.
